DUPLEX PLUG-IN DEVICE

Arthur M. Draving, Feasterville, Pa., assignor, by
mesne assignments, to Hugh H. Eby, Fort
Wayne, Ind.

Original application December 30, 1939, Serial
No. 311,791. Divided and this application
September 26, 1942, Serial No. 459,798

3 Claims. (Cl. 173—328)

This invention relates to duplex plug-in socket devices.

While it is not broadly new in the art to provide socket devices with contacts so arranged as operatively to receive a plurality of different plug-in devices in alternative selection, yet in the past so far as is known, such multi-duty socket devices have had independent and distinct female contact elements for each of the prongs of the plug-in devices. This both complicates and increases the cost of the socket devices.

This invention is a division of my co-pending application, Serial Number 311,791 filed Dec. 30, 1939, now issued as Patent No. 2,296,839, dated September 29, 1942.

It is among the objects of this invention: to provide a simplified contact having two separate prong receiving portions; to provide a socket with two prong apertures in combination with a single female contact element having portions operatively associated with each aperture to receive and to establish firm electrical contact with a male prong in either opening; to provide an electrical contact device arranged for the creation of an electrical contact with prongs inserted therein in alternative laterally spaced positions; to provide a contact element for sockets arranged to establish intimate electrical contact with either of two prongs of different diameters; to provide a socket element with two different aperture patterns with female contact elements mounted on the socket overlapping selected apertures from both patterns whereby two-plug-in devices having prongs arranged in different patterns may alternatively be associated operatively with the socket with the prongs in the related apertures of the two patterns electrically engaging a common contact in the socket; to provide a socket device arranged to receive in alternation two plug-in devices having prongs of different pattern arrangements; to provide a socket device with a single female contact arrangement so disposed in the socket as alternatively to receive and establish electrical engagement with prongs of different sizes or positions; to provide multi-duty sockets for plural plug-in devices which may be comprised either of a single or multiple molding or of suitably punched or apertured laminated sheets or combinations of moldings and laminated sheets; to improve contact for socket devices; to provide a socket device which shall incorporate in a single unit the practical and effective functions of two alternatively used sockets of forms heretofore in general use; to provide a socket device in which the number of operatively possible

positions in which electrical contact may be established with an inserted prong exceeds the number of separate and distinct prong receiving contact elements; and many other objects will become more apparent as the description proceeds.

In the accompanying drawing forming part of this description:

Fig. 1 represents a fragmentary plan partially broken away of a form of laminated socket utilizing a contact according to this invention engaged between the lamination.

Fig. 2 represents a similar view of a modified form of laminated socket with a contact threaded through the lower plate.

Fig. 3 represents a side elevation of the socket according to Fig. 1.

Fig. 4 represents a side elevation of the socket according to Fig. 2.

Figs. 5 and 6 represent respectively plans of the blank and of the completed contact as provided for association with the laminated sheets of Fig. 1 and as subsequently bent to form the contact for the socket of Fig. 2.

Fig. 7 represents a bottom plan of a modified form of a molded socket utilizing a slightly modified contact incorporating the invention, with the bottom plate removed.

Fig. 8 represents a top plan thereof.

Fig. 9 represents a side elevation thereof.

Referring to Fig. 5, the generally T-shaped blank shown comprises the shank 10, having a suitable soldering aperture 11 at one end and at the other connecting through the restricted neck 35 12 with the cross piece 13 substantially aligned with the shank 10. The cross piece 13 has side edges 14 and 15 generally normal to the end edge 16 and the rear edges 17. The blank has a central backing portion 18. Although the blank of Fig. 5 is shown as being substantially symmetrical, it is contemplated that it may be asymmetrical so that the portion of the cross piece 13 terminating in the side edge 15 may be longer than the complementary portion ending in the side edge 14, especially for the construction of the contact of Fig. 6.

It will be understood that the cross piece 13 has the side edges curled up in relation to its central backing portion 18 to form semi-cylindrical side arms 20, 21 (Fig. 6) terminating in the respective edges 14 and 15 which latter are brought into close but spaced adjacency to each other and to the backing portion 18 which, when bent so that the backing portion 18 is perpendicular to the shank 10, describes a pair of semi-

cylindrical prong embracing members 20, 21 the axes of which are normal to the shank 10. As shown in Fig. 6 the prong embracing members have different diameters and this asymmetry is provided by imparting a further bend to the portion 21 whereby the edge 15 is brought closer to the backing portion 18 than the edge 14 to that portion. The prong embracing members 20, 21 may have the same diameter and be symmetrical.

The ears 22 and 23 extend from the edge 17 of cross piece 13 and form lateral supports for the contact when inserted in a plug-in device.

In the use of the invention it is assumed, for purposes of illustration that one plug-in device is provided with multiple prongs adapted to enter either the larger apertures 57, 58, and the third one over the contact shown in plan (Figs. 1 and 2), or the enlarged portion of apertures 65 and 71 (Fig. 8), and another plug-in device has multiple prongs adapted to enter the smaller apertures 60, 61 and the small one over the contact shown in plan, constricted portion 72 (Fig. 8). In Figures 1 and 2 the apertures of different size are disposed in triangular relation. In Figures 7 and 8 they are disposed in annular relation. In the embodiments thus shown there is one position of adjustment in which the respective prongs can enter the respective apertures in their pattern arrangement so that the circuit making is predetermined. As the prongs pass downwardly through the respective apertures they enter and are embraced by the respective prong embracing members 20 or 21, of the respective compound contacts 10.

In the laminated socket Figs. 1 to 4, inclusive, the upper plate 56 carries the prong receiving enlarged apertures 57 and 58 leading to the enlarged end 20 of the contact and is also provided with a blind small aperture 61 passing through both plates, and the prong contact small aperture 60, as well as one not shown, for registration with the small contact end 21 of the contact disclosed in Figs. 1 and 2. The upper plate 56 of Figs. 1 and 3 is secured to the lower plate 55 by suitable means such as a central rivet or the like 62, and the soldering tails 10 project laterally of and between the two plates. Lower plate 55 has a plurality of elongated holes 54 of generally oval profile, to receive the contact parts comprised of the backing portion 18 and arms 20 and 21, with the lugs 22 and 23 overlying the plate to support the contact, especially during the entry of the prong contacts therein. In Figs. 2 and 4 the upper plate 56 is identical with that of Figs. 1 and 3, and the lower plate 55 is only modified far enough to provide a slot 63 beside enlarged opening 54, so that the neck 12 can be constituted as a reach between the contact making portions and the reentrantly bent soldering tail 10 threaded through the slot 63.

It will be noted that in Figures 1 and 2 the prong receiving arms 20, 21 of contact 10 lie slightly in the apertures 57, 58 and 60. The projecting ears 21, 22 form lateral supports for the contact and extend through and depend from the bottom of the plate 55.

The multi-duty contact of this invention is also applicable to those types of socket wherein a plurality of prongs are arranged in two concentric annular series for alternative use. As shown in Figs. 7 to 9 inclusive, the molded base 64 has a plurality of laterally tapering openings 65 extending radially of the perpendicular axis passing centrally of the screw receiving aperture

66. Each aperture terminates at the upper end in a shoulder 68, and forming a slot 70 in the lower surface. A contact similar to that of Fig. 6 but with reduced offset shanks 67 is provided for each aperture, with a little end 21 in the narrower part 72 of the aperture. The ears 22, 23 may, or may not, be present as desired. The contacts are all held in place by a suitable device such as by a fibre plug (not shown). The use of the sockets of Fig. 7, for two different plug-in devices having prongs in another series, but of different diameters, will be understood. The prongs of larger diameter enter at 71 while those of lesser diameter enter at 72.

15 I claim as my invention:

1. A socket for plug-in devices comprising a mounting support comprising a lower plate having a laterally elongated aperture permitting the entry of a prong of a plug-in device in two laterally spaced parallel positions, a contact mounted on the support and having integral portions forming a pair of spaced parallel substantially semi-cylindrically shaped prong-embracing members on a backing strip disposed in said aperture with the respective axes of the members substantially perpendicular to said lower plate, arranged to be engaged and to form electrical contact with prongs in either of said spaced positions, said mounting support further comprising an upper plate disposed in substantially parallel slightly spaced relation to the lower plate, means on the contact overlapping the upper surface of the lower plate, and said upper plate having a pair of spaced prong receiving apertures registering with the respective integral prong-embracing members of the contact.

2. A socket for plug-in devices comprising a mounting support comprising a lower plate having a laterally elongated aperture permitting the entry of a prong of a plug-in device in two laterally spaced parallel positions, a contact mounted on the support and having integral portions forming a pair of spaced parallel substantially semi-cylindrically shaped prong-embracing members on a backing strip disposed in said aperture with the respective axes of the members substantially perpendicular to said lower plate, arranged to be engaged and to form electrical contact with prongs in either of said spaced positions, said mounting support further comprising an upper plate disposed in substantially parallel slightly spaced relation to the lower plate, means on the contact overlapping the upper surface of the lower plate, and said upper plate having a pair of spaced prong-receiving apertures registering with the respective integral prong-embracing members of said contact, and of different diameters.

3. A socket for a plurality of plug-in devices of different effective prong patterns, comprising a base having a plurality of apertures in its upper surface conformable with the reception alternately of plug-in devices of different effective prong patterns, an integral contact having a plurality of spaced parallel substantially semi-cylindrical shaped prong-embracing members on a backing strip, means mounting the contact in the base with the respective prong-embracing members in operative prong receiving relation to a plurality of apertures containing apertures from each such pattern with the respective members in position to receive a prong axially of the prong and member.
